UNITED STATES PATENT OFFICE

THOMAS B. FLANAGAN, OF COLUMBUS, OHIO, ASSIGNOR TO THE EXACT WEIGHT SCALE COMPANY, OF COLUMBUS, OHIO, A CORPORATION OF OHIO

DESIGN FOR A WEIGHING SCALE

Application filed January 3, 1929. Serial No. 29,493. Term of patent 14 years.

To all whom it may concern:

Be it known that I, THOMAS B. FLANAGAN, a citizen of the United States, and a resident of Columbus, in the county of Franklin and State of Ohio, have invented a new, original, and ornamental Design for a Weighing Scale, of which the following is the specification, reference being had to the accompanying drawings, forming a part hereof.

Figure 1 is a front perspective view of the weighing scale showing my new design.

Figure 2 is a side perspective view thereof.

Figure 3 is a horizontal sectional view taken through the base of Figure 1 looking upwardly to show the plate and tower.

I claim:

The ornamental design for a weighing scale, as shown.

THOMAS B. FLANAGAN.
